(57) **CLAIM**
The ornamental design for a roadway luminaire, as shown and described.

DESCRIPTION

FIG. 1 is an isometric view of a top, front, and right side of an ornamental design for a roadway luminaire;

FIG. 2 is an isometric view of a bottom, front, and right side view of the roadway luminaire of FIG. 1;

FIG. 3 is a top plan view of the roadway luminaire of FIG. 1; FIG. 4 is a bottom plan view of the roadway luminaire fixture of FIG. 1;

FIG. 5 is a right side elevational view of the roadway luminaire fixture of FIG. 1, a left side elevational view of the roadway luminaire being a mirror image of the right side elevational view;

FIG. 6 is a front elevational view of the roadway luminaire of FIG. 1; and,

FIG. 7 is a rear elevational view of the roadway luminaire of FIG. 1.

The broken lines are for the purpose of illustrating environmental structure and form no part of the claimed design. The dash-dot lines are for the purpose of defining the bounds of the claimed design and form no part of the claimed design.
